UNITED STATES PATENT OFFICE

ELLARD L. YOUNGER, OF WOODLAND, CALIFORNIA, ASSIGNOR TO E. L. YOUNGER & SONS, OF WOODLAND, CALIFORNIA, A COPARTNERSHIP COMPOSED OF E. L. YOUNGER, ELLARD L. YOUNGER AND M. A. YOUNGER

DEHYDRATOR

Application filed December 13, 1927. Serial No. 239,642.

The invention relates to dehydrators for foods such as fruit and the like, and particularly to dehydrators which operate by effecting a circulation of heated and relatively dry air through the food as it is moved progressively through the dehydrator.

A general object of the invention is to provide an improved dehydrator of the type shown in Patent Number 1,648,468 which was issued to me under date of November 8, 1927.

A specific object of the invention is to provide in a dehydrator of the class described, means so regulating and controlling the application of the drying heat to the food that a maximum drying temperature may be used without danger of applying excessive temperatures which might damage the food.

Another object of the invention is to provide in a dehydrator of the character described, a tempering compartment for effecting a preliminary heating of the food at an adjusted temperature generally below that at which the major part of the drying operation is effected, such compartment being directly included in the air circulating system of the dehydrator.

A further object of the invention is to provide in a dehydrator of the class described means facilitating a removal of test specimens of the dried product while the product is disposed in the dehydrator.

A still further object of the invention is to provide in the dehydrator means cooperating with trays carrying the food for confining the air circulation entirely to a predetermined path.

Yet another object of the invention is to provide in the dehydrator, improved means for adjustably controlling the inlet of fresh air thereto.

Still another object of the invention is to provide an improved dehydration process which the apparatus of the present invention is particularly arranged to carry out.

The invention possesses other objects and features of advantage, some of which, with the foregoing, will be set forth in the following specification and the accompanying drawings, in which:

Figure 1 is a plan sectional view generally

at the ceiling line of a dehydrator embodying my invention.

Figure 2 is a fragmentary elevation of a sealing means utilized in confining the circulated air to a predetermined path. 55

Figure 3 is a sectional view taken on the line 3—3 in Figure 2.

Figure 4 is a longitudinal sectional view taken on the broken line 4—4 in Figure 5.

Figure 5 is a view taken on the line 5—5. 60 in Figure 1.

Figure 6 is an enlarged fragmentary view of a radiator of the dehydrator.

Figure 7 is a sectional view taken on the line 7—7 in Figure 6. 65

Figure 8 is an enlarged fragmentary section through a pair of superposed trays in which the food is carried for conveyance through the dehydrator.

As herewith particularly illustrated, the apparatus of the dehydrator is disposed in a housing structure 1 including side walls 2, a rear wall 3, an open front section 4, a roof 5, and a furnace pit 6. The structure 1 is divided longitudinally to provide the pit 6, 75

a blower and radiator compartment 7, and a drying chamber 8, it being noted that a considerable portion of the burner pit 6 underlies the compartment 7. A furnace 9 is provided in the pit 6, such furnace being of a 80

usual construction and having a burner 11 for a fluid fuel at its forward end. The heated air and products of combustion are arranged to escape from the furnace through a flue portion 12 at the rear of the furnace and 85

thence upwardly through a specially constructed radiator 13 in the compartment 7 to an upper flue portion 14 which discharges above the roof 5. Preferably, and as shown, 90

a suction fan 15 is provided in operative association with the upper flue section 14 for effecting a positive draft through the furnace and radiator.

The drying chamber 8 is provided with a depressed floor portion 16 extending transversely across the housing structure between inlet and outlet doors 17 and 18 respectively. 95

Tracks 19 are provided on the floor portion 16, such tracks extending through both of the door openings 17 and 18 and being arranged 100

to

to carry trucks 21. As herewith disclosed, two parallel lines of tracks are provided whereby two lines of trucks 21 may be simultaneously sent through the drying chamber. Stacks or tiers 22 of trays 23 are arranged to be mounted on the trucks 21, and the trays 23 are formed with cut down front and rear ends 24 whereby passages are defined between the trays and transversely of the tracks. Preferably, and as shown, the tray stacks of successive trucks abut, and such stacks extend close to the roof, while a whole number of tray stacks is arranged to closely fit between the inlet and outlet doors 17 and 18 respectively when these doors are closed. In this manner, the stacks of each line of trucks are arranged to cooperate to provide a partition across the drying chamber 8 whereby air directed thereagainst from either side 20 will be caused to pass between the trays of the stacks and so through the food on the trays.

Means are provided for effecting a continuous circulation of air through the stacks of trays, such means preferably comprising a blower fan 25. The blower 25 is here shown mounted upon a horizontal partition or floor 26 overlying the furnace 9 in spaced relation therefrom whereby a fresh air inlet passage 27 is defined, such passage connecting the 30 open front 4 of the structure with the compartment 7. Preferably, the passage 27 is provided with means for adjustably controlling the size of the inlet opening thereto, and, as here shown, the means provided comprises 35 a damper 28 of the sliding door type, it being noted that the outlet of the passage 27 is so related to the stream of air circulated by the blower 25 that such stream will tend to draw in a certain amount of fresh air through the 40 passage 27, and that the provision of the damper 28 permits an adjusted control of the rate of admission of fresh air to the circulated air stream to meet varying requirements as to the moisture content and temperature of 45 the circulated air, and other factors relating to the effective operation of the apparatus.

The blower 25 is provided with a rearwardly-flared discharge hood 29 which terminates in a vertical plane at the forward edge of the 50 depressed floor portion 16, with the outlet thereof extending from the ceiling 5 to the bottom of the tray stacks 22 and from opposite sides of the central pairs of tray stacks. In this manner, the air stream from the 55 blower 25 primarily passes through the two central stacks 31 of each line thereof, it being noted, however, that the number of stacks in each line so treated may be varied without departing from the spirit of the invention. 60 The blower 25 may be driven in any suitable manner, and is here shown belted to a motor 32 suspended from the roof of the structure and out of the circulation stream of the blower.

65 The rear space of the drying chamber 8

which lies between the last line of tray stacks and the rear wall 3 is arranged to function as a manifold for distributing the air supplied thereto through the central stacks 31. Preferably, and as shown, this space is divided centrally thereof by a vertical partition 33 to provide chambers 34 and 35, such partition extending longitudinally of the structure from the wall 3 to terminate adjacent the stacks of the rear line thereof. In this manner, the air passing through the stacks 31 is arranged to be divided between the chambers 34 and 35. Preferably, and as shown, the partition 33 is formed to provide cylindrically concave reflecting surfaces 36 and its forward edge lies in the plane of abutment of the stacks 31 of a line thereof. Formed in the rear wall 3 adjacent and at opposite sides of the partition 33 are openings 37 provided with hinged doors 38 arranged to be fixed in a plurality of adjusted open positions to permit the escape of a predetermined volume of over-humid air, the amount of air thus escaping being generally complementary to that introduced through the fresh air inlet passage 27 which is controlled by the damper 28. The settings of the doors 38 and damper 28 are determined by a reading of a hygrodeik 39 mounted in the chamber 34 and arranged to be read through a peep-hole 41 in the rear wall 3.

It will now be noted that at least two stacks of trays are arranged to be included in each row thereof on either side of the central stacks 31. As here shown, stacks 42 and 43 are respectively disposed adjacent the inlet and outlet doors 17 and 18 respectively, while stacks 44 are disposed between these stacks and the central stacks 31. Extending forwardly from the wall 3 in the planes of abutment of the stacks 42 and 43 with adjacent stacks 44 are partitions 45 and 46 respectively, each partition being provided with an opening extending generally the full height thereof, and having hinged doors 47 and 48 respectively in the openings. The doors 47 and 48 are hinged at their edges which are closer to the wall 3 and are arranged to be adjustably disposed across the chambers 34 and 35 respectively in such a manner as to provide an adjustable control of the air flow to the stacks 42 and 43 respectively, it being generally desirable that the circulation flow of air through these stacks be not as rapid as is that through the stacks 31 and 44.

The air flowing forwardly through the stacks 42, 43 and 44, it will now be noted is arranged to flow back to the blower through the passage 49 defined by the space of the compartment 7 about the blower hood 29, a partition 51 being provided across the compartment forwardly of the blower for confining the air stream, it being noted that the blower is here shown of the type in which the air is received axially from either side thereof.

and is discharged radially outwardly therefrom. The fresh air inlet passage 27, it is noted, is arranged to discharge into the passage 49 as at outlets 52 adjacent the hood 29.

Heretofore, it has been a usual practice in dehydrators of the present type, to pass the air from a blower through a radiator and then directly to the food to be dried. But such practice has, through the possibility of uneven heating and the high temperature primarily given to the drying air, frequently resulted in a scorching or partial cooking of the fruit first reached by the air stream, and an unsatisfactory and unevenly dried product has resulted. In accordance with the present invention, however, such difficulties are avoided by disposing the radiator in the passage 49. Accordingly, and as shown, the radiator 13 is formed with side sections 53 connected by inlet and outlet manifolds 54 and 55 respectively at the top and bottom of the radiator, such manifolds being respectively connected to the lower and upper flue portions 12 and 14. The radiator sections 53 may be of any suitable structure for facilitating the radiation of heat therefrom, as here shown, they are formed with a succession of secondary manifolds 56 connected to each other by horizontal pipes 57. In this manner, the incoming air from the passage 27 is thoroughly mixed with the air heated by the radiators before the heated air is delivered to the central tray stacks 31. To ascertain the condition of the product in the trays of stacks 43, a hand-hole 58 is preferably provided in the wall 2 adjacent and forwardly of the stack 43 of the forward line of trays whereby specimens of the product may be taken without opening the dehydrator. Doors 59 are also preferably provided in the wall 2 for effecting an entry to the compartment 7 while the apparatus is filled with the tray stacks.

Since it is highly desirable that the air stream set up by the blower 25 be strictly confined to the fixed paths indicated in Figure 1, means are preferably provided for sealing the junctures of the various partitions and walls with the stacks of trays. Accordingly, and as shown, flaps 61 are provided at the vertical edges of such partitions, such flaps being preferably formed of a relatively stiff pliable fabric which is disposed to resiliently engage the stacks and at the same time will permit the progression of the stacks through the apparatus. When, as is particularly shown, more than one row of trays is provided for, posts 62 are provided in appropriate position between the rows of trays, such posts being also provided with the flaps 61. In practice, it has been found desirable to use posts of T-section for the support of the various flaps 61, which flaps may each be formed of a section of four inch cotton belting. In this manner, a positively controlled and com-

plete circulation of the drying air is assured, and escape of the air from the apparatus is minimized.

It will now be noted that when the apparatus is filled with the stacks of trays and the heated air is being circulated through the system described, the circulation of air through the stacks 42 at the inlet doors 17 is arranged to be somewhat less than that through the adjacent stacks 44 whereby the air in passing through these stacks is somewhat cooler than the remainder of the circulated air, it being noted that the lowering of the temperature is primarily due to the necessary preheating of the food which was initially at the temperature of the outside air and the slower rate of admission of circulated air to the stacks 42 through the use of the draft control door 47.

In this manner, the dryer chamber portion at the stacks 42 is arranged to function as a preheating and tempering chamber from which the stacks 22 are arranged to be thereafter advanced to the remainder of the positions across the apparatus. Preferably, the draft door 48 controlling the flow of air to the stacks 43 nearest the exit side of the apparatus is also closed somewhat to limit the circulation rate through these stacks, whereby the temperature thereat is also somewhat less than that in the adjacent stacks 44. In practice, it has been found that best results are obtained if the doors 47 and 48 are so set as to provide an average temperature for the air in the stacks 42 which is about fifteen Fahrenheit degrees less than that of the air through the central stacks 31, while the temperature in the stacks 43 is about seven and a half Fahrenheit degrees less than that of the air through the central stacks. The air temperature in the stacks 44 would be generally five degrees cooler than that of the central stacks. In this manner, the stacks are arranged to be exposed to drying air of progressively different temperatures as they are moved through the apparatus, with the maximum temperature to which they are subjected an allowable one for the particular food to be treated.

Different foods will, of course, have maximum allowable dehydrating temperatures, thus for French prunes the maximum is 165° Fahrenheit, with the other temperatures slightly lower as has been described. It will be noted that the graduated temperatures of the treatment thus provided, the uniformity of temperature at any point in the circulated air stream, and the uniform and regulated humidity of the air, combine to produce a particularly uniform and superior product.

I claim:

1. In a fruit dehydrator providing a dryer chamber through which a confined stream of air is directed in fixed paths laterally through a line of fruit disposed across the chamber,

the method of tempering the fruit at both ends of the line which comprises effecting a slower flow of air at said line ends solely by expanding said stream thereat.

- 5 2. In a dehydrator providing a dryer chamber through which a confined stream of air is directed in fixed paths laterally through a line of material to be dried, said line of material extending across the chamber and being arranged for longitudinal advancement through the chamber, the method of tempering the fruit at the rearward end of the line which comprises effecting a slower flow of air at said rearward line end than at the intermediate portions of the line.
